UNITED STATES PATENT OFFICE.

GEORGE H. F. SCHRAADER AND HENRY PHILLIP KRAFT, OF NEW YORK, N. Y.;
SAID KRAFT ASSIGNOR TO SAID SCHRAADER.

VALVE.

SPECIFICATION forming part of Letters Patent No. 531,392, dated December 25, 1894.

Application filed June 8, 1894. Serial No. 513,878. (No model.)

To all whom it may concern:

Be it known that we, GEORGE H. F. SCHRAADER and HENRY PHILLIP KRAFT, citizens of the United States, residing in the city, county, and State of New York, have jointly invented 5 certain new and useful Improvements in Valves, of which the following is a specification.

This invention relates most particularly to 10 valves for pneumatic tires.

Our invention aims to provide a valve stem and head in which the washer will be maintained firmly in position against either distortion or escape and without injurious compression, and such a stem and head which 15 can be constructed easily and economically on the most diminutive scale required.

To this end in carrying out the preferred form of the invention we construct the stem 20 and head as will be hereinafter described.

In the accompanying drawings Figure 1 is an axial section of a tire valve supplied with our improved stem. Fig. 2 is a similar view showing the parts in the open position and 25 the stem in elevation. Fig. 3 is a view of the stem, cup and washer separated. Fig. 4 is an axial section of a modified construction of valve provided with our improvements. Fig. 5 is an elevation of the stem and an axial 30 section of the head and cup showing a modification in their construction, and Fig. 6 is an axial-section showing another modification.

Referring to Figs. 1 to 3 inclusive let A represent the tubular valve body; B, the seat 35 thereof; C, the inner valve chamber thereof; D, the valve stem; E, the valve proper or head; F, the washer; G, the spring beneath the head; H, the bottom plug; I, the mouth or inlet duct of the valve; J, the nut engaging the stem; K, 40 the washer therefor, and L the outer face of the body A against which this washer bears.

According to the preferred form of our invention the stem and head are constructed as shown in Figs. 1, 2 and 3, the stem 45 consisting of a plain cylindrical body a passing through the throat b of the seat B, a screw threaded outer end c, a recessed inner end d, a square shoulder e between this recess and the portion a, a cylindrical enlargement f at 50 bottom of the recess b, a wide flat face g be-

neath this enlargement, and a solid body h, preferably coned on its under face beneath the face g and constituting the lower end of the stem and the backing of the head. The head consists of the lower end of the stem, 55 and a cup shaped washer i fixed thereon. This washer i has a central perforation or aperture j preferably cylindrical and fitting over the enlargement f of the stem, a flat annular bottom k surrounding this aperture, 60 and an annular vertical flange l united to the bottom by a curve m. The bottom k of the cup seats on the face g, and then is fixed thereto by swaging or upsetting the enlargement f over on the inner face of the bottom. 65 This preferably makes an air tight, permanent and rigid connection between the cup and body h. The flange l is preferably cylindrical, and when the cup is fixed to the stem this flange is nearly flush with the top 70 face of the washer F, and in the same plane with the shoulder e, as shown. Preferably the stem and the body h are formed on a single integral spindle.

When the cup and stem are fixed together, 75 as shown in Fig. 1, they constitute a stem and head having an annular washer chamber M, the bottom of which is composed of the over-set top of the enlargement f, the adjacent exposed top face of the bottom k of the cup, and 80 the inner annular face of the flange l, for the outer side and bottom walls of the compartment, the shoulder e for the top of the compartment, and the cylindrical wall of the reduced portion d of the stem for the inner wall 85 of the compartment. Into this compartment the washer F, which is a cylindrical disk of rubber having flat top and bottom faces, a central perforation and vertical walls, is seated by passing its perforation over the 90 screw threaded end of the stem and springing it beneath the shoulder e. Its perforation tightly fits the recess d beneath the shoulder, and hence the latter prevents its upward movement. The cylindrical edges of the 95 washer fit snugly within the flange l of the cup. Thus it is held firmly against radial distortion. When thus held the washer is exposed opposite the seat throughout the annular portion of its top face which lies be- 100

tween the stem and the flange, and this portion is engaged by the seat B when the valve is closed.

In operation the washer is compressed by the seat into the chamber M when the valve is drawn tight, and makes a tight joint with the seat and with the interior of the chamber, but is prevented from becoming distorted. When the valve is open the washer resumes its normal position. If the rubber adheres to the brass seat after prolonged closure, it will be separated therefrom by the shoulder e when the valve opens. Should a washer become worn out it can be picked out of the compartment by any suitable tool and a new one substituted.

In the construction of stems and heads of the character described the parts are so exceedingly small that it is impracticable to construct a one piece stem and piston in which the compartment M is turned out, and hence heretofore it has been necessary to dispense either with the central recess and shoulder or with the external flange.

Our invention permits the easy and economical construction of a stem and head having these advantageous features. The stem can be readily turned to the contour shown, and any drawn or stamped metal cup applied to it. The upsetting of the two metals to fix them together is easily accomplished. In the construction shown in Fig. 3 this is done by placing a punch against the enlargement f and striking it down thereon with sufficient force to cause the metal to flow over the adjacent portion of the cup.

It will be understood that the invention is not limited to the particular construction set forth as the preferred form, nor to any special construction of valve. On the contrary the two parts composing the stem and head may be variously disposed as circumstances suggest, and the device as a whole may be employed with any valve.

Fig. 4 shows a different construction of valve in which the shell lettered A' has a riveted cross bar H' maintaining the spring G, and a modified construction of nut lettered K' is fixed to the stem lettered D' by an enlargement N formed on the head of the latter. The other parts are substantially identical to those previously described.

Fig. 5 shows a stem and head in which the stem lettered D'' has a still further reduced end n below its recess d, and the head lettered E'' is of turned metal having integral flange f' and a downwardly tapering body h', the latter having an axial hole o through which the end n of the stem passes, and at the bottom of which it is riveted to lock the parts together.

Fig. 6 shows a stem lettered D³ having beneath its recess d a conical body h³ and an enlarged end p, and the cup lettered i' consists of a separate piece of thin drawn metal having a cylindrical flange f³ at the top and a tapering body q which is spun in against the

tapering body of the stem and held thereon by the enlargement p.

Either of these constructions are effective to provide a two piece stem and head having a washer compartment with side flanges and a top shoulder in which the washer can be properly held.

What we claim is—

1. In a valve, a shell having an annular valve seat, a throat above said seat, and a chamber beneath said seat, in combination with a valve proper consisting of a stem having a screwthreaded outer end, a reduced portion inwardly of said seat, a shoulder between its screw threaded end and said reduced portion, an enlarged body beneath said reduced portion having a tapering under face at bottom, and an annular flange at top surrounding said reduced portion, a packing washer within said flange embracing the reduced portion of said stem beneath the shoulder of the latter and engaging said seat when the valve is closed, and a nut screwing on the end of said stem embracing the exterior of said shell and drawing said washer against said seat to close the valve, all combined and arranged substantially as and for the purpose set forth. 75

2. In a valve, a shell having an annular valve seat, a contracted throat therethrough, and an enlarged chamber at the inner side of said seat, in combination with a valve proper consisting of a stem and head, said stem having a screwthreaded outer end projecting through and beyond said throat, a reduced portion at the inner side of said seat, a shoulder between said reduced portion and its screwthreaded end, and an enlarged body at its inner end beyond said reduced portion and within said chamber, said stem and body all formed in one integral piece, a sheet metal annular flange seated on and carried by said body opposite said reduced portion, and an annular packing washer embracing the reduced portion of said stem bearing against the enlarged body thereof, embraced externally by said sheet metal flange, and engaging said sheet when the valve is closed, and a nut screwing on the end of said stem engaging the exterior of said casing and holding said valve proper seated when the valve is closed, all combined and arranged substantially as and for the purpose set forth. 95

3. In a valve, a casing having an annular seat, a contracted throat, and an enlarged chamber, in combination with a valve proper consisting of a stem and head, said stem having an outer screwthreaded end projecting through said throat, a reduced portion at the inner side of said throat, a shoulder between said reduced portion and outer end, an annular enlargement having an overhanging flange at the inner end of said reduced portion, and a body at the inner end of said enlargement, all formed in one integral piece, a cup-shaped sheet metal piece embracing said enlargement beneath the overhanging flange thereof, 120 125 130

seating on said body and having an annular flange opposite said reduced portion of said stem, and an annular packing washer embracing said reduced portion within the flange 5 of said cup-shaped piece and engaging said seat, and a nut screwing on the end of said stem and engaging the exterior of said shell for holding the valve closed, all combined and arranged substantially as and for the purpose 10 set forth.

4. A valve stem and head consisting of the stem *D* of turned metal having a screw-threaded end *c*, shoulder *e*, reduced recess *d*, enlargement *f*, top face *g* and body *h*, and a 15 metal cup *i* having an aperture *j* fitting over

said enlargement, a bottom *k* engaging said face, and annular flange *l* opposite said recess *d*, said enlargement overhanging said cup and thereby fixing it in position, and a rubber washer seated in said recess and within said 20 flange.

In witness whereof we have hereunto signed our names in the presence of two subscribing witnesses.
